UNITED STATES PATENT OFFICE.

FRANK N. COOLEY AND GEORGE R. COOLEY, OF SEATTLE, WASHINGTON; SAID GEORGE R. COOLEY ASSIGNOR TO SAID FRANK N. COOLEY.

PNEUMATIC-TIRE-INFLATING APPARATUS.

Application filed May 8, 1922. Serial No. 559,138.

To all whom it may concern:

Be it known that we, FRANK N. COOLEY and GEORGE R. COOLEY, citizens of the United States, residing at Seattle, in the county of King and State of Washington, have invented certain new and useful Improvements in Pneumatic-Tire-Inflating Apparatus, of which the following is a specification.

10 This invention relates to tire-inflating apparatus and its object is the provision of efficient apparatus of this character which may be conveniently employed to supply pneumatic tires with air to a predetermined pressure.

Other more specific objects and advantages of the invention will appear in the following description.

The invention consists in the novel construction, adaptation and combination of parts hereinafter described and claimed.

In the accompanying drawings,—

Figure 1 is a front elevation of a stand in which is mounted apparatus embodying our invention. Fig. 2 is a vertical longitudinal section of the upper portion of Fig. 1. Fig. 3 is a transverse section taken substantially through 3—3 of Fig. 2. Fig. 4 is a detail sectional view illustrating the settable devices for governing the pressure regulator.

In said drawings, the reference numeral 5 represents a casing which is provided with a vertically disposed bore 6 for a cylindrical valve 7 having intermediate its length a peripheral groove 8.

Said casing is also provided at opposite sides of said bore with axially aligned passages 9 and 10 which are located to be in register with the groove 8 of said valve when the latter is in its lowermost position.

The casing is furthermore provided with a by-passage 11 affording communication between the passage 10 and the bore 6 below said valve.

12 represents a pipe for making connection between a duct 9¹ leading into the passage 9 and a source or reservoir, not shown in the drawing, of compressed air. 13 represents a pipe connecting with the passage 10, said pipe being adapted to have attached thereto a flexible hose 14 through which air is delivered to a pneumatic tire for inflating

the same. The hose is provided at its outlet end with any ordinary or suitable tire-valve coupling, not shown, provided with a check valve which serves to prevent the escape of air when the coupling is disconnected from a tire-valve.

The casing 5 is provided in axial alignment with the bore 6 and above the same with a chamber 15 of greater diameter than the bore to receive in its upper end a plunger 16. Between the plunger and a collar 17 rigid upon the valve is a helical spring 18 which tends to yieldingly retain the collar against the bottom of the spring-containing chamber and have the valve in the position in which it is represented in Fig. 3. The plunger 16 has an extension 19 formed with teeth 20 to constitute a rack which is engaged with a spur pinion 21.

This pinion is rigidly mounted upon a horizontal shaft 22 disposed axially of a cylindrical shell 23 which, together with the aforesaid casing, is secured to a supporting stand such as 24.

The pinion shaft 22 is journaled in bearings 25 and 26 which are respectively provided in a bracket attachment provided internally of the shell and in the rear wall 27 of the shell.

Secured to and extending radially from the rear end of said shaft is an arm 28 which above the shell extends forwardly as at 29.

Secured to or formed integral with the rear end of the shell is a flange 30 disposed concentrically with respect to the shaft 22. Engageable against the inner surface of said flange is a block 31 which is secured to the offset end 32 of a rod 33 extending into a tubular handle 34 provided on the arm part 29. The rod 33 has secured to its upper extremity a push button 35 which protrudes from the outer end of the handle.

The block 31 is frictionally held in engagement with the flange 30 as by means of a helical spring 36 interposed between the button 35 and a bushing 37 secured within the inner end of the handle 34.

38 represents a fluid-pressure gauge of any known or suitable construction secured within the shell 23 and concentrically thereof and is operatively connected by means of a tube 39 with the passage 10.

As illustrated, said gauge is provided with

a hand 40 for pointing off upon an arcuate scale 41 provided on the gauge face the pressure of air obtaining at the delivery side of the valve 7.

- 5 42 represents a pointer secured to the arm part 29 to indicate with respect to the markings of scale 41 the pressure which it is desired to deliver air through the hose 14 to inflate a tire.
- 10 To employ the above described apparatus to effect the delivery of air to inflate a tire to a predetermined pressure, as eighty pounds for example, the operator adjustably moves the arm 28 through the medium of the 15 handle 34 to present the pointer 42 at the scale mark denoted by "80" on the gauge face.

To facilitate the positioning of the pointer the operator disengages the friction block 31 20 from the casing flange 30 by exercising a thumb pressure against the button 35.

In moving the pointer to a selected position the arm 28 transmits rotary motion to the shaft 22 and pinion 21 to cause the latter to raise or lower the rack 19 whereby the effective power of the spring 18 is regulated to balance the desired pressure, as eighty pounds for example, obtaining in the discharge side of the valve 7 and against 30 the underside of the latter.

When the pressure exceeds that for which the spring 18 is regulated the valve is elevated into a position to stop the flow of air from the passage 9 into the delivery passage 10.

When the air pressure in the passage 10 is below that of the spring's power, as indicated by the pointer 42, the spring serves to restore the valve into the inoperative position in which it is represented in Fig. 3.

What we claim, is,—

1. In pneumatic tire-inflating apparatus, the combination of a pressure-reducing valve, a casing for said valve and provided with a supply port and a discharge port, a by-pass communicatively connecting said discharge port with the casing bore below said valve, a scale of pressure indicating marks, a plunger, a spring interposed between said plunger and the valve for yieldingly retaining the latter in position to afford a passage between said ports, a rack rigid with said plunger, a shaft, a pinion mounted on the shaft and engaging the rack, an arm connected to said shaft for regulating said spring through the medium of the rack and pinion, and a pointer carried by said arm and arranged to cooperate with the scale for indicating the positioning of the arm to effect predetermined adjustments of the spring.

2. In a pneumatic tire-inflating apparatus, the combination of a cylindrical valve provided with an air passage, a casing hav-

ing a vertically disposed bore to receive said valve and provided with a supply port and a discharge port at diametrically opposite sides of the bore, a by-pass communicatively connecting said discharge port with said bore below the valve, a scale of pressure indicating marks, a plunger, a spring interposed between said plunger and the valve for yieldingly retaining the latter in position to have the passage thereof in register with both of said ports, a rack rigid with said plunger, a shaft, a pinion mounted on the shaft and engaging the rack, an arm connected to said shaft for regulating said spring through the medium of the rack and pinion, and a pointer carried by said arm and arranged to cooperate with the scale for indicating the positioning of the arm to effect predetermined adjustments of the spring.

3. In a pneumatic tire-inflating apparatus, the combination of a cylindrical valve provided with an air passage, a casing having a vertically disposed bore to receive said valve and provided with a supply port and a discharge port at diametrically opposite sides of the bore, a by-pass communicatively connecting said discharge port with said bore below the valve, a fluid pressure gauge operatively connected with said discharge port, said gauge being provided with a scale of pressure indicating marks, a plunger, a spring interposed between said plunger and the valve for yieldingly retaining the latter in position to have the passage thereof in register with both of said ports, a rack rigid with said plunger, a shaft, a pinion mounted on the shaft and engaging the rack, an arm connected to said shaft for regulating said spring through the medium of the rack and pinion, a pointer carried by said arm and arranged to cooperate with the gauge scale for indicating the positioning of the arm to effect predetermined adjustments of the spring, and means for releasably securing the same in selected positions.

4. In a pneumatic tire-inflating apparatus, the combination of a cylindrical valve provided with an air passage, a casing having a vertically disposed bore to receive said valve and provided with a supply port and a discharge port at diametrically opposite sides of the bore, a by-pass communicatively connecting said discharge port with said bore below the valve, a fluid pressure gauge operatively connected with said discharge port, said gauge being provided with a scale of pressure indicating marks, a plunger, a spring interposed between said plunger and the valve for yieldingly retaining the latter in position to have the passage thereof in register with both of said ports, a rack rigid with said plunger, a shaft, a pinion mounted on the shaft and engaging the rack, an arm

connected to said shaft for regulating said spring through the medium of the rack and pinion, a pointer carried by said arm and arranged to cooperate with the gauge scale for indicating the positioning of the arm to effect predetermined adjustments of the spring.

Signed at Seattle, Washington, this 24th day of April, 1922.

FRANK N. COOLEY.
